BELT BUCKLE

Frank J. Bomersheim, Royal Oak, Mich.

Application December 27, 1952, Serial No. 328,224

7 Claims. (Cl. 24—77)

This invention relates to a belt buckle and is a continuation-in-part of my prior copending application Serial No. 93,360, filed May 14, 1949.

It is an object of this invention to provide a belt buckle which is attractive in appearance and easily manipulable to effectively secure the ends of a belt in a plurality of adjustable positions.

In the drawings:

Fig. 1 is a fragmentary front view of the buckle in the operative locked position on a belt.

Fig. 2 is a front view of the buckle alone.

Figs. 3 and 4 show the opposite ends respectively of a belt usable with the buckle of this invention.

Fig. 5 is a section view along the line 5—5 in Fig. 1.

Fig. 6 is an end view of the buckle.

Fig. 7 is a side view of the buckle.

Referring to the drawings and particularly to Fig. 1, it will be observed that the buckle generally designated 10 is adapted to be used with a belt generally designated 12. The buckle is preferably formed out of metal such as steel or the like and shaped to provide an outer wall that is defined by two spaced apart panels 14 and 16 which are generally of the same size and shape. Panels 14 and 16 are spaced longitudinally of the buckle so as to define an opening 18 between the opposed free edges 20 and 22 of the buckle. Along their upper and lower edges panels 14 and 16 are bent at right angles to form top and bottom walls 24 and 26, respectively. The top and bottom walls 24 and 26 are turned inwardly towards each other to form the inner wall of the buckle which is defined by flanges 28 and 30. Flanges 28 and 30 extend in a plane generally parallel to the plane of panels 14 and 16 and are spaced therefrom a distance corresponding approximately to twice the thickness of the belt 12 with which the buckle is to be used.

One end 32 of the belt is provided with a clip member 34. Clip 34 may be secured to the end 32 of the belt by any suitable means such as rivets 36. Clip 34 is fashioned with a return bent lug 38 which is spaced from the portion of the clip which is riveted to the belt. Adjacent its opposite end the belt is provided with a series of longitudinally spaced apertures 40 which are arranged to be engaged by a hook 42 on the buckle. Hook 42 preferably includes a flat rectangular portion 44 which is generally of the same size and shape as the lug 38 of clip 34. Hook 42 also includes a leg 46. Hook 42 is permanently secured as by soldering to panel 16 on the outer face thereof with the leg 46 abutting against the free edge 22 of panel 16 and projecting rearwardly toward flanges 28 and 30. Leg 46 terminates at its free end in a hook portion 48 which is spaced outwardly of the plane of flanges 28 and 30.

In use, the buckle is attached to the belt by slipping the buckle endwise over the end 32 of the belt until lug 38 clears the free edge 20. The end 32 of the belt is then retracted to engage the lug 38 around the free edge 20 of panel member 14. Edge 20 is centrally notched as at 50 to accommodate the reverse bent portion of the

2

clip which defines the lug 38. This firmly anchors the end 32 of the belt on the buckle when tension is applied to the belt. The end of the belt is adjustably secured to the buckle by slipping the end of the belt through the opposite end of the buckle and sliding this end of the belt on flanges 28 and 30 beneath the hooked portion 48 of leg 46 and also beneath the opposite end 32 of the belt. The belt is tightened in this manner to a position wherein one of the openings 40 is aligned with the leg 46 on the hook 42. Then the user slips his thumb behind the buckle and presses the belt outwardly to engage the leg 46 with its hook portion 48 in the aligned opening 40 of the belt. The tension in the belt thereby securely holds it in a locked position with respect to the buckle.

Thus, it will be seen that I have provided a belt buckle of unique construction which is not only easily operated to secure the ends of a belt in an adjusted position but which is also very attractive. The formation of the panels 14 and 16 at opposite ends of the buckle provides the buckle with a very symmetrical appearance. Between these panels a portion of the belt is visible. If the buckle and the belt are made of contrasting colors, this provides an attractive appearance. The appearance of the belt is further enhanced by the symmetrical disposition of the lug 38 and the flat generally rectangular portion 44 of hook 42.

I claim:

1. A buckle comprising a hollow metal body including a pair of longitudinally spaced, substantially flat outer panels, opposed longitudinally extending top and bottom walls extending at right angles from said outer panels and interconnecting the same, opposed spaced inturned lower flanges extending from said walls parallel to said outer panels and extending throughout the length of said outer panels, a clip attachable to one end of a belt projected between one of said outer panels and said lower flanges and having a reverse turned tongue retainingly engageable over the inner edge of said one outer panel, and a tongue centrally secured to the corresponding inner edge of the other outer panel having a depending and out-turned portion extending towards said lower flanges and adapted for retaining registry within one of a plurality of transverse slots formed at the other end of said belt projected between said other outer panel and said lower flanges.

2. A buckle for use with a belt comprising juxtaposed inner and outer walls, top and bottom walls extending along the longitudinal edges of said inner and outer walls and connecting said inner and outer walls in parallel spaced apart relation, said inner and outer walls being spaced apart a distance generally corresponding to twice the thickness of the belt to be used with the buckle, said outer wall comprising a pair of substantially flat panels spaced apart longitudinally of the buckle and extending vertically between said top and bottom walls, said panels being symmetrically disposed relative to the buckle and having opposed, spaced apart free edges, a generally U-shaped clip member adapted to be attached to one end portion of belt which is projectable through one end of said buckle for engagement with said free edge of one of said panels to anchor said end portion of the belt on the buckle, and a hook member on the other panel projecting inwardly toward said inner wall, said hook member being selectively projectable through one of a plurality of longitudinally spaced openings in the opposite end portion of the belt when said opposite end portion of the belt is inserted through the opposite open end of the buckle in a position underlying the first mentioned end portion of the belt.

3. The belt buckle defined in claim 2 wherein said panels are of generally the same shape and size and extend to the opposite ends of the buckle.

4. The belt buckle defined in claim 3 wherein said

inner wall comprises a pair of flanges extending along the inner longitudinal edge of said top and bottom walls.

5. A buckle for use with a belt comprising juxtaposed inner and outer walls, a pair of top and bottom walls extending along the longitudinal edges of said inner and outer walls and connecting said inner and outer walls in parallel spaced apart relation, said outer wall comprising a pair of substantially flat panels spaced apart longitudinally of the buckle and extending vertically between said top and bottom walls, said panels being symmetrically disposed relative to the buckle and having opposed, spaced apart free edges in the plane thereof, a generally U-shaped clip adapted to be attached to one end of the belt, said end of said belt being projectable through one end of the buckle to engage said clip with said free edge of one of said panels, said other panel having an inwardly projecting hook member adjacent its said free edge, said hook member being selectively engageable with one of a plurality of longitudinally spaced openings adjacent the other

end of the belt when said other end of the belt is inserted through the opposite end of the buckle in a position underlying the first mentioned end of the belt.

5. The belt buckle defined in claim 5 including means forming a notch in said free edge of one of the panels adapted for interengagement with said U-shaped clip member.

10 6. The belt buckle defined in claim 5 wherein said U-shaped clip member has a portion adapted to overlie the outer face of the panel with which it is engaged, said hook member having a portion overlying and secured to its associated panel, said two last mentioned portions being generally of the same size and shape.
